UNITED STATES PATENT OFFICE.

HORACE M. SMITH, OF CHICAGO, ILLINOIS, ASSIGNOR TO LIQUID CARBONIC COMPANY, OF CHICAGO, ILLINOIS, A CORPORATION OF ILLINOIS.

DRINK-MIXER.

1,318,021.

Specification of Letters Patent.

Patented Oct. 7, 1919.

Application filed March 23, 1918. Serial No. 224,119.

To all whom it may concern:

Be it known that I, HORACE M. SMITH, a citizen of the United States, residing at Chicago, county of Cook, and State of Illinois, have invented certain new and useful Improvements in Drink-Mixers, of which the following is a specification.

My invention is more particularly concerned with drink mixers which are used 10 in connection with or attached to soda fountains where carbonated beverages are dispensed. It has for its object to provide a drink mixer of simplified construction and mode of operation, which occupies less 15 space than the apparatus of this character formerly employed, requires less attention and is less apt to cause trouble and get out of order.

In the accompanying drawings I have 20 illustrated and in the following specification described in detail a preferred form of drink mixer. It is to be understood, however, that the specific disclosure is for the purpose of exemplification only and that 25 the scope of the invention is defined in the following claims in which I have endeavored to distinguish it from the prior art so far as known to me without, however, relinquishing or abandoning any portion or feature thereof.

My improved device comprises a stand adapted to be clamped or otherwise secured to a counter or fountain and which carries a motor stationarily mounted thereon driving 35 the mixing tool, the stand having a pivoted rest plate for the glass adapted when released to swing down out of operative position and controlling, according to its position, the switch by which the motor is 40 governed.

In the drawings.

Figure 1 is a front elevation partly in section of a preferred form of my invention;

Fig. 2 is a side elevation thereof also 45 partly in section; and

Fig. 3 is a detail in vertical section on the lines 3—3 of Fig. 1 looking in the direction of the arrows.

The stand is in the nature of a hollow 50 casting 3 adapted to rest at its lower end 4 upon a flat surface and having a clasp 5 secured thereto by screws 6. The clamp may be provided with the usual thumb screw 7 to bear against the under side of 55 the shelf or counter to which the device is

attached. At its upper end the casting is offset forwardly as at 8 and formed with a split casing 9 which contains the motor, of any ordinary or approved construction, the casing being provided with upper and 60 lower bearings 10, 11 for the armature spindle 12 which projects through the lower bearing and is provided with a socket 13 for the mixing tool 14. The support or table 15 for the glass is pivoted on a bolt 65 or arbor 16 which is secured in lugs or posts 17, 18 rising from the flange 19 of the clamp. The construction of the clamp and the stand is such that the glass support may be swung to the position shown in full line in Fig. 2 70 to support the glass or drop to the position shown in dotted lines in order to permit the removal of the glass vertically downward to clear the mixer 14 without spilling the contents of the glass. At or near one edge 75 of the glass support but extending on the opposite side of the pivot therefrom is a heel or extension 20 having a downwardly turned end 21 to stop the upward movement of the glass support when it reaches 80 the horizontal.

In order to maintain the glass support in its raised or horizontal position, I provide a bolt or latch 22 which is mounted for reciprocation in lugs 23, 24 extending upward from the surface of the clamp member 5. The nose 25 of the latch is beveled as shown and the heel or extension 20 of the glass support is correspondingly beveled at 26 so that when the glass support is 90 thrown upward the heel striking against the latch forces the latter inward until the heel has cleared the beveled nose thereof. The latch may be notched as at 27 to receive the heel when in horizontal position. 95 After the heel has passed the latch the latter is driven forward to the position shown in Fig. 1 by a spring 28 compressed between lug or post 23 and a collar or washer 29 and surrounding the latch. In order to operate 100 the latch to release the tumbler support, I provide a push button 30 on a push rod 31 which is connected at its rear end to the latch by means of a plate 32 into which said latch and push rod are threaded. The push 10 rod, as well as the latch, is guided in holes provided for the purpose in the posts or standards 23, 24.

The switch for making and breaking the circuit to the motor is mounted upon an in- 11

sulating board or plate 33 which is sealed and protected within the stand and secured to brackets 34, 35 by screws 36. For convenient access to the switch the face of the stand is open opposite thereto as at 37, the opening being covered by a cover plate 38. The switch is shown as of the common knife form, the blade 39 being pivoted at 40 to the plate and engaging the spring contact 41 in the usual manner. The connection for the outside wire is shown in dotted lines at 42. The blade is provided with a bell-crank 43 which is connected by spring 44 with a plate 45 mounted on the upper end of a reciprocating rod 46. The rod 46 is guided as at 47 in a lug on plate 33 and carries at its lower end a head 48 which is connected by pin and slot connection 49 with a lug 50 projecting from the tumbler support 15.

0 An arm 51 on rod 46 strikes bell crank 43 when the tumbler support 15 is lowered, to force said crank past the dead center and so open the switch.

Preferably the glass or tumbler support 5 is annular at 52, the opening being shou- 0 dered at 53 and threaded at 54 to receive a threaded disk 55. A disk 56 of rubber or the like may be interposed between disk 55 and the shoulder 53 to form a suitable surface 0 on which to rest the glass.

The operation of the device will now be obvious. Normally the glass support is in the position shown in dotted lines in Fig. 2 and the switch in the off or open position. 5 When a glass of soda or the like is to be stirred it is applied vertically to the stirrer and the swinging support then raised to the horizontal position shown in full lines. The latch snaps over the arm or heel 20 holding 0 the support in horizontal position. At the same time the switch actuating rod is lowered by reason of its described connection to the tumbler support to the position shown in dotted lines in Fig. 1 in which, just after 5 the spring 44 has passed the dead center with reference to the bell-crank, the switch blade is snapped to closed position. The current is thus turned into the motor and the latter continues to actuate the stirrer 0 until intervention by the attendant. When the glass of material has been sufficiently stirred, the attendant, taking the glass in his hand, releases the glass support by pressing the button 30, when the support drops, 5 at the same time raising the switch actuating rod so that the spring 40 passes to

the other side of the pivot of the switch, in which position it exerts a tension to open the switch. With my improved device the stirring or mixing of a drink requires the 60 minimum of attention and as the removal of a glass of liquid is impossible without at the same time turning off current from the motor, waste of current due to the operation of the motor when no work is to be 65 performed is avoided.

I claim:

1. In a device of the class described, a stand, a motor carried by the stand, a stirrer driven by the motor, a tumbler support 70 pivoted below the stirrer to oscillate to and from the same, a latch for holding the tumbler support in horizontal position and means for operating the latch to release the tumbler support.

2. In a device of the class described, a stand, a motor mounted on the stand, a stirrer driven by the motor, a tumbler support pivoted to the stand and having a rear- 80 wardly extending heel, a horizontally sliding latch adapted to engage said heel, means normally pressing the latch into engagement with the heel, and a push rod for releasing the latch from the heel.

3. In a device of the class described, a 85 stand, a motor mounted on the stand, a stirrer driven by the motor, a tumbler support pivoted to the stand to oscillate toward and from the stirrer, a switch controlling the motor, a connection between the mov- 90 able element of the switch and the tumbler support for operating the former from the latter, and means for latching the tumbler support in horizontal position.

4. In a device of the class described, a 95 stand, a motor mounted on the stand, a stirrer driven by the motor, a pivoted tumbler support movable toward and from the stirrer, a latch for holding the tumbler support in horizontal position, a switch mount- 100 ed within the stand and controlling the supply of current to the motor, said switch comprising a movable blade having a bell-crank member, a vertically reciprocable rod connected to the tumbler support and oper- 105 ated thereby, the upper end of said rod being adapted to pass the pivot of the movable switch member, and a spring connecting the upper end of said rod with the bell-crank arm of the movable switch member.

HORACE M. SMITH.
